CONTAINER

James R. Watkins, Niles Center, Ill.

Application September 12, 1932, Serial No. 632,748

11 Claims. (Cl. 217—12)

This invention pertains to containers in general and particularly to those which may be collapsed for shipment and the frame members of which are connected together by fiber board or the like.

5 In general the object of this invention is to provide improvements in collapsible crates, and particularly such improvements as involve the use of fiber board or some other similar inexpensive sheet material for securing and hinging together

10 the rigid members of a crate.

The advantages of the invention and the manner of using it are well illustrated by the following description of a crate having wooden members secured to fiber board, certain of the walls of the 15 crate being hinged to one another at the score lines on a continuous piece of fiber board.

The various particular objects and advantages of the invention will be alluded to and will become apparent in the specification which follows.

20 Fig. 1 is a perspective of one form of crate made in accordance with this invention;

Fig. 2 is a central horizontal cross section of the same crate;

Fig. 3 is a view of a detachable bottom of the 25 crate;

Fig. 4 is a horizontal sectional view of a corner of a crate;

Fig. 5 is a perspective of a modified form of the invention;

30 Fig. 6 is a partial perspective of the modification shown in Fig. 5; and

Fig. 7 is a partial section of a modified corner of the crate.

Referring now to Figs. 1 to 4, inclusive, a single 35 sheet of fiber board generally referred to as 1 is provided with score lines positioned so that the fiber board may be bent to form the rectangular structure shown in Fig. 2. Prior to bending, however, a plurality of wooden strips 2, 3, 4, 5, 6, 7, 8, 9, and 10 are tacked, glued, or otherwise 40 firmly secured to one surface of the fiber board so that when the latter is folded these strips will all be on the outside. The fiber board will then be folded and the two end margins 11 and 12 will 45 preferably be overlapped and be glued or otherwise secured together and tacked to a vertical wooden strip 13, or they may be both glued and tacked. On two opposite sides of the structure horizontal strips or cleats 14, 15, 16, and 17, are 50 provided which unite the vertical strips which they adjoin. A cover and a bottom for the structure is then formed, being alike and preferably constructed as indicated in Fig. 3 wherein a piece of fiber board 17' is secured in any suitable manner, as by tacks, to the three cleats 18, 19, and 20.

Fig. 2 shows that the four vertical sides of the 55 crate when constructed as shown are capable of being collapsed flatly, and as the cleats are on the outside surface they do not interfere with collapsing.

When the crate has been arranged in its normal rectangular shape the top and bottom closure members may readily be inserted between the 60 protruding ends of the vertical cleats 7, 8, 9, 2, 3, and 4. Nails may then be driven through the 65 ends of each of the last six mentioned vertical cleats and through the ends of the six horizontal cleats which are provided on the top and bottom portions of the crate. When the structure is so 70 assembled and nailed the crate members are all interlocked and are capable of standing together without further support, even if the fiber board were then cut away. However, with the fiber board secured to each of them at closely spaced 75 points, with as many tacks as one may desire to use, or glued to them, the fiber board and the wood cleats reinforce one another and form a structure which affords a surprising resistance to 80 compression, distortion, and damaging thrusts of many kinds. This surprising strength, however, is attained with the use of inexpensive material, especially light in weight, and so arranged that 85 four of the walls may be collapsed together into a compact package while the other two walls may be readily disposed in the same flat package. Thus the cost of shipping these crates from the 90 crate manufacturer to the user will be very little indeed, while the work of assembling the crates to enclose the user's merchandise will require little time, no skill and a negligible expense.

The modified form shown in Figs. 5 and 6 contains even further advantages. The four vertical sides of this container are provided with scoring at positions which will form the wall corners and the margins are overlapped and secured together 95 as in Fig. 1. Each of the four vertical walls is provided with a pair of integral flaps connected at score lines, one at the top and one at the bottom. The flaps 21 and 22 will be folded inwardly first as are the corresponding flaps at the 100 bottom of the crate. The flap 23, however, is provided with a cleat 24 and the flap 25 is provided with a similar cleat 26. These latter flaps are the last to be folded in.

The arrangement of the wood cleats on the 105 vertical walls of the modified form of container differ from those shown in Fig. 1. One wall has horizontal cleats 27 and 28 the lower margin of the bottom cleat coinciding with the score line of the bottom flap, while the top surface of the 110

upper cleat coincides with the score line on the flap 22. The ends of both of these cleats protrude beyond the corner of the crate far enough so that they may be nailed to similar horizontal cleats on the next adjacent side walls. In between the horizontal cleats 27 and 28 are vertical cleats 29 and 31. The four cleats on this panel of the wall may be secured at frequent intervals to the fiber board and to each other by suitable nails.

10 An assembly of cleats similar to that just described is placed on the opposite wall of the container while at the two remaining opposite side walls the cleats are arranged as follows.

15 Horizontal cleats 32 and 33 are secured to the fiber board far enough below the top and bottom edges of the wall and extend beyond the vertical corners so that when the container is being collapsed they just slide under the cleats 27 and 28 but do not protrude far enough so that their ends 20 will interfere with the vertical cleats such as cleat 29. These horizontal cleats are also connected to each other by vertical cleats 34 and 35. The arrangement of cleats on the wall opposite the last described wall is obviously the same although 25 it is not fully shown in the drawings.

It is clear that the modified form shown in Figs. 5 and 6 may readily be collapsed when the top and bottom flaps are folded open as shown in Fig. 6. The horizontal cleats near the top and bottom 30 edges of the side walls merely slide past one another during the collapsing operation but when the crate is opened up these ends may readily be nailed together while the cleats carried by the top and bottom flaps may be nailed against the 35 horizontal cleats which are attached to two of the side walls.

All of the cleats may be secured to the fiber board while it is entirely flat, before the two margins corresponding to the margins 11 and 12 of 40 Fig. 2 are secured together on the vertical cleat 31. It is clear that the attaching of all of these cleats to a flat piece of scored fiber board may be done rapidly and inexpensively. The joining of the fiber board after folding by tacking its margins to the cleat 31 is also a simple step. Thereafter the entire structure can be re-collapsed with the flaps extended as indicated in Fig. 6 and the structure shipped compactly but ready for instant extension and assembly.

50 To form this structure into a rigid interlocked crate structure nails need be driven only through the protruding ends of the eight horizontal cleats such as cleats 27, 28, 32, and 33, and through the cleats carried by the top and bottom flaps.

55 When this latter structure is assembled and nailed together it forms a rigid crate whose wooden cleat members are all interlocked and capable of remaining so even though the fiber board were all cut away. But the fiber board and cleats reinforce each other when made in accordance with 60 this invention to afford a container of remarkable strength. The fiber board further more serves as the means by which all four vertical walls are hinged to each other to permit of collapsibility and by means of which the eight flaps 65 are hingedly secured to the vertical walls.

Fig. 7 shows another manner of overlapping the end margins of the fiber board forming the mutually hinged side walls. The margin 12 is 70 placed on the inside of the container so that its edge is practically in the corner of the box. Thus the interior surface of the container is smooth and free of seams.

75 For convenience and simplicity the appended claims refer to all the vertical walls of the illus-

trated containers as "side walls", while the tops and bottoms of the same containers are termed "end walls".

It should be understood that this invention is capable of employing materials other than those mentioned and may be embodied in structures which may differ from those preferred forms herein shown, but which will nevertheless retain the principles and advantages of the invention as defined in the claims which follow.

I claim:

1. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having sustaining cleats on its walls, positioned to avoid interference with said collapsing, extending from end to end of the members united thereto for reinforcement thereof and positioned to be secured by nails or the like to said marginal portions, said cleats having sufficient strength and rigidity to 100 constitute a major sustaining means between the two end closure members.

2. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having sustaining cleats on its outside walls extending from end to end united thereto for reinforcement thereof and positioned to be secured by nails or the like to said marginal portions, said cleats having sufficient strength and rigidity to 110 constitute a major sustaining means between the two end closure members.

3. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having projecting cleats on its 120 walls, positioned to avoid interference with said collapsing, extending from end to end united thereto for reinforcement thereof and positioned to be secured by nails or the like to said marginal portions, said cleats having sufficient strength and rigidity to 130 constitute a major sustaining means between the two end closure members.

4. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having projecting cleats on its outside walls extending from end to end united thereto for reinforcement thereof and positioned to be secured by nails or the like to said marginal portions, said cleats having sufficient strength and rigidity to 140 constitute a major sustaining means between the two end closure members.

5. A crate assembly comprising, in combination, three preformed and complete component parts comprising two rigid end closure members having rigid marginal portions suitable for receiving 150

nails or the like, and a collapsible tubular member formed from a single sheet of stiff fibrous material forming side walls scored for folding at their junctures for collapsing, the last said member having sustaining cleats on its walls, positioned to avoid interference with said collapsing, extending from end to end of the member united thereto for reinforcement thereof and positioned to be secured by nails or the like to 10 said marginal portions, said cleats having sufficient strength and rigidity to constitute a major sustaining means between the two end closure members.

6. A crate assembly comprising, in combination, three preformed and complete component parts comprising two rigid marginal portions suitable for receiving nails or the like, and a collapsible tubular member of stiff fibrous sheet material forming side walls foldable at their 15 junctures for collapsing, the last said member having rigid sustaining cleats secured at closely spaced points intermediate their ends to said walls extending from end to end of the member and positioned thereon to avoid interference with 20 said collapsing, the end portions of said cleats being positioned to be secured by nails or the like to said marginal portions, said cleats having sufficient strength and rigidity to constitute a major sustaining means between the two end 25 closure members.

7. A crate assembly comprising, in combination, three members completely preformed for subsequent assembly comprising two rigid end closure members having rigid marginal portions, 30 and a collapsible tubular member of stiff sheet material forming side walls and foldable at the wall junctures for collapsing and having sustaining cleats on its walls, positioned to avoid interference with said collapsing, extending from end 35 to end of the member united thereto for reinforcement thereof, the end portions of the cleats being located for rigid connection to said marginal portions, said cleats having sufficient strength and rigidity to constitute a major sustaining means between the two end members.

8. A crate assembly comprising, in combination, three members completely preformed for subsequent assembly comprising two rigid end closure members having rigid marginal portions, 40 and a collapsible tubular member of stiff sheet material forming side walls and foldable at the wall junctures for collapsing and having sustaining cleats on its outside walls extending from end to end of the member united thereto for reinforcement thereof, the end portions of the 45 cleats being located for rigid connection to said marginal portions, said cleats having sufficient strength and rigidity to constitute a major sustaining means between the two end members.

60

9. A crate assembly comprising two preformed rigid end closure members and a preformed collapsible tubular member, the latter comprising side walls formed of stiff fibrous sheet material connected and conditioned at the corners for collapsing, rigid cleats, positioned to avoid interference with said collapsing, secured thereto at closely spaced points intermediate their ends extending from end to end of the member with some of the cleats protruding beyond the ends of the member, the end closure members having rigid marginal portions suitable for receiving nails or the like for rigidly securing said marginal portions to the said wall cleats, said cleats having sufficient strength and rigidity to constitute a major sustaining means between the two end closure members.

10. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having sustaining cleats on its walls, positioned to avoid interference with said collapsing, extending from end to end of the member united thereto at closely spaced points for substantially continuous longitudinal reinforcement thereof and positioned to be secured by nails or the like to said marginal portions, said cleats having sufficient strength and rigidity to constitute a major sustaining means between the two end closure members.

11. A crate assembly comprising, in combination, three preformed and complete component parts comprising two rigid end closure members having rigid marginal portions suitable for receiving nails or the like, and a collapsible tubular member of stiff fibrous sheet material forming side walls foldable at their junctures for collapsing, the last said member having sustaining cleats on its walls, positioned to avoid interference with said collapsing, extending from end to end of the member united thereto for reinforcement thereof, the cleats on two opposite side walls being positioned to be secured to said marginal portions by nails or the like extending in the plane of the end closure members, the cleats 120 on the other two opposite side walls being positioned relatively to their adjoining said marginal portions to be secured thereto by nails or the like extending perpendicular to the planes of the end closure members.
